Inventor:

Harvey Webster

United States Patent Office

HARVEY WEBSTER, OF CAMBRIDGE, VERMONT.

Letters Patent No. 78,095, dated May 19, 1868.

IMPROVED THILL-COUPLING.

The Schedule referred to in these Letters Patent and making part of the same.

TO ALL WHOM IT MAY CONCERN:

Be it known that I, HARVEY WEBSTER, of Cambridge, in the county of Lamoille, and State of Vermont, have invented a new and improved Mode of Coupling and Uncoupling Thills; and I do hereby declare that the following is a full and exact description thereof, reference being had to the accompanying drawings, and the letters of reference marked thereon.

Figure 1, perspective, showing coupling closed.

Figure 2, longitudinal section, coupling open.

To enable others skilled in the art to make and use my invention, I will proceed to describe its construction and operation.

I make the thill-iron D, axle-iron E, and the clamp F, in the usual way. I make the bolt, G, plain, that is, omitting the usual head, screw, and nut, and cut it to a length flush with the outside of the ears h h. I then add the wedge-plate A, the cap or bolt-holder B, and spring C, to the axle-iron, in the manner as shown, or any other, substantially the same.

To uncouple the thills from the vehicle, place the fingers underneath and behind the flange of wedge-plate A, and pull forward until the bolt-cap B uncovers the bolt G; at the same time, push the bolt through the thill-iron. The coupling is done in same manner, pushing the bolt G into the thill-iron.

I make the plate A in the form of a wedge, for the purpose of forcing the thill-iron D and bolt G tightly together, thereby obviating all rattle and wear of the parts mentioned.

The whole device to be applied to vehicles in the usual manner.

What I claim as my invention, and desire to secure by Letters Patent, is—

The wedge-plate A, bolt-holder or cap B, and the spring C, as applied to thill-couplings, and operated either by draught or pressure, all for the purpose herein specified.

HARVEY WEBSTER.
